UNITED STATES PATENT OFFICE.

FRANKLIN ELLIS, OF TROY, ASSIGNOR TO THE PETTIBONE MANUFACTURING COMPANY, OF CINCINNATI, OHIO.

DESIGN FOR A BADGE.

SPECIFICATION forming part of Design No. 23,816, dated November 27, 1894.

Application filed July 23, 1894. Serial No. 518,396. Term of patent 7 years.

To all whom it may concern:

Be it known that I, FRANKLIN ELLIS, a citizen of the United States, residing at Troy, in the county of Miami and State of Ohio, have 5 invented and produced a certain new and original Design for a Badge, of which the following is a specification, reference being had to the accompanying drawing, in which the design is shown in elevation.

10 The leading feature of my design consists in the figures of a man and a bear in the attitude of combat, encircled by a rope-like ornamentation, the bear being shown in an erect

posture grappling with the man who is intended to represent a savage holding an up- 15 lifted knife in one hand.

What I claim is—

The design for a badge substantially as herein shown and described.

In testimony whereof I have hereunto set 20 my hand.

FRANKLIN ELLIS.
